DESIGN FOR AN ELECTRICAL CONDENSER

Haim Beyer, New York, N. Y., assignor to Cornell-Dubilier Corporation, New York, N. Y., a corporation of New York

Application February 23, 1935, Serial No. 55,584

Term of patent 14 years

To all whom it may concern:

Be it known that I, Haim Beyer, a citizen of the United States, and residing in the county of, city of, and State of New York, at 229 East 79th Street, have invented a new, original, and ornamental Design for Electrical Condensers, of which the following is a specification, reference being had to the accompanying drawing, forming part thereof.

Figure 1 is a plan view of an electrical condenser, showing my new design.

The bottom side of the condenser has applied thereto the same design as the top side shown in Figure 1. Figure 2 is a side elevational view, and Figure 3 is a front elevational view of Figure 1.

I claim:

The ornamental design for an electrical condenser, substantially as shown and described.

HAIM BEYER.
